FREQUENCY MODULATION SYSTEM

Raymond M. Wilmette, Washington, D. C.

Application December 26, 1941, Serial No. 424,521

9 Claims. (Cl. 250—20)

This invention relates to frequency modulation radio receivers, and, particularly, to an improved circuit for reception and detection of a signal in the presence of another of nearly equal intensity covering parts of a common frequency band, making it possible to reduce the degree of interference beyond that obtainable by previously known means. This application is related to my copending application Number 424,522, filed December 26, 1941.

Heretofore, frequency modulation receivers have been able to separate signals occupying a common frequency band when the amplitude ratio between them was of the order of two to one or more, leaving comparatively little interference. This result is obtained by using a well-known circuit known as a limiter.

It is an object of this invention to provide means for effectively increasing the ratio of the signals before reaching the limiter, whereby a signal may be received satisfactorily in the presence of an interfering signal of more nearly equal intensity than is possible at present.

In the drawing:

Figure 1 shows in the form of a block diagram a feed-back circuit.

Figure 2 shows a similar circuit as in Figure 1, but in which the feed-back is super regenerative.

Referring now to Figure 1, the conventional components of a frequency modulation receiver, which will be first described, include an antenna 2 and ground 4, respectively, connected to the input of radio frequency amplifier 6 which is connected to a detector 8. A beat from oscillator 10 is combined with the output of radio frequency amplifier 6 in detector 8 and passed to intermediate frequency amplifier 12 and thence through limiter 14, discriminator 16, audio frequency amplifier 18 and finally to speaker 20.

The ratio of the desired and undesired signal normally remain the same up to the input of the limiter circuit. The limiter circuit distorts the wave form and has the effect of increasing the ratio of the desired to undesired signal.

The invention is concerned with the case where two or more signals, for instance, signals hereinafter termed A and B, impinge upon antenna 2, signal A, which is frequency modulated being stronger than signal B. In the normal receiver signal A would be interfered by signal B. In order to increase the effective ratio between the signals, an attenuator 22, which is variable, as indicated at 24, is connected across the output of limiter 14 ahead of discriminator 16 and connected by a feed-back line 26 through circuit 28

which may be used to control the phase and amplitude. The output of circuit 28 which is connected back into intermediate frequency amplifier 12, is indicated at 30. The phase and amplitude are adjusted so that regeneration is obtained without oscillation. The signals fed back are at the same ratio or intermediate frequency as the signal input to the limiter but they cover a different frequency swing. Strictly speaking, therefore, they are not of the same frequency as the signals of the input of the limiter. The frequency swings at the input and output of the limiter, however, are of such a nature that the frequency modulation will correspond to the same audio signals. For convenience, the term "basic frequency" will be used. When two signals have the same carrier frequency and the same type of modulation but have a different frequency swing, the signals will be said to have the same basic frequency. When the weaker signal is frequency modulated, the ratio of the frequency swing of signal A, relative to that of signal B is greater at the output of the limiter than at the input. When the weaker signal is amplitude modulated, its degree of modulation is greatly reduced by the limiter and there is also produced some phase modulation. The regeneration, therefore, will be greater for signal A than for signal B and will produce an effect equivalent to increasing the effective ratio of signal A to signal B at the input of the limiter. With regeneration, therefore, the ratio of signal A to signal B will be effectively greater at the input of the limiter than at the input of the receiver. The interference caused by signal B will therefore be decreased or eliminated.

The feed-back may also be adjusted as in a super regenerative receiver as shown in Figure 2 where the receiver oscillates periodically. By this means the regenerative effect is substantially increased. The signals are received on antenna 102, amplified in 106, mixed with the signal from oscillator 110, in detector 108, amplified in the intermediate frequency amplifier 112, passed through a limiter 114, thence through a discriminator 116, an audio amplifier 118 and a loud speaker 120, a portion of the output of the limiter is taken by means of a potentiometer 122 with a tap 124 through a circuit 128 back to the intermediate frequency amplifier 112, at 130. The oscillator 131 feeding into the amplifier 112 causes oscillation of the feed-back circuit periodically in the manner well known in the art for super regeneration.

The invention described above is not limited to

the specific disclosure, but should be given the full range of substitutions and equivalents within the scope of the following claims. Specifically, for instance, the invention is applicable when the signals are of the same carrier frequency. It is also applicable with other forms of feed back than that specifically described above. It is also applicable when the type of modulation of the weaker signal is other than frequency modulation.

What I claim is:

1. The method of receiving one of two signals occupying a common portion of two overlapping frequency bands, the stronger signal being frequency modulated, which comprises receiving said signals together, increasing the ratio of the stronger signal to the weaker signal and feeding back a portion of the signals after their ratio has been increased, the basic frequencies of the portion of the signals fed back and of the said two signals being the same.

2. The method of receiving one of two signals occupying a common portion of two overlapping frequency bands, the stronger signal being frequency modulated, which comprises receiving said signals together, increasing the ratio of the amplitude of the modulation of the stronger signal relative to the other and feeding back a portion of the signals after the ratio of the amplitude of their modulation has been changed, the frequencies of the portion of the signals fed back and of the said two signals being the same.

3. In a frequency modulated radio receiving system, means for separating first and second signals occupying a common portion of two overlapping frequency bands, the first signal being stronger and frequency modulated, comprising means for receiving the first and second signals, modifying means whereby the ratio between said first and second signals in the output of said modifying means is increased compared with the ratio of said first and second signals at the input of said modifying means, and circuit means for feeding back a portion of the output of said modifying means into the input of said modifying means, said circuit means being such that at the input of said modifying means the basic frequencies of the portion of the signals fed back and of the said first and second signals are the same.

4. In a frequency modulated radio receiving system, means for separating first and second signals occupying a common portion of two overlapping frequency bands, the first signal being stronger and frequency modulated, comprising means for receiving the first and second signals, modifying means whereby the ratio of the amplitude of the modulation of said first signal relative to the amplitude of the modulation of said second signal in the output of said modifying means is increased compared with the ratio of the amplitude of the modulation of said first signal relative to the amplitude of the modulation of said second signal at the input of said modifying means, and circuit means for feeding

back a portion of the output of said modifying means into the input of said modifying means, said circuit means being such that at the input of said modifying means the basic frequencies of the portion of the signals fed back and of the said first and second signals are the same.

5. The combination claimed in claim 3, and means in said circuit means for modifying the phase and amplitude of the fed-back portion.

10 6. The combination claimed in claim 4, and means in said circuit means for modifying the phase and amplitude of the fed-back portion.

7. In a frequency modulated radio receiving system, means for separating first and second simultaneous signals occupying a common portion of two overlapping frequency bands, the first signal being stronger and frequency modulated, comprising a means for receiving the first and second simultaneous signals, first means for amplifying simultaneously said signals, second means having an input connected to the output of said first means, whereby the ratio of said first and second signals is greater in the output of said second means than in the input of said second means, and circuit means for feeding back a portion of the output of said second means into the input of said first means, said circuit means being such that the input of said first means, the basic frequencies of the portion of the signals fed back and of the first and second signals are the same.

15 8. In a frequency modulated radio receiving system, means for separating first and second simultaneous signals occupying a common portion of two overlapping frequency bands, the first signal being stronger and frequency modulated, comprising a means for receiving the first and second simultaneous signals, first means for amplifying simultaneously said signals, second means having an input connected to the output of said first means, whereby the ratio of the amplitude of the modulation of said first signal relative to the amplitude of modulation of said second signal is greater in the output of said second means than in the input of said second means, and circuit means for feeding back a portion of the output of said second means into the input of said first means, said circuit means being such that the input of said first means, the basic frequencies of the portion of the signals fed back and of the first and second signals are the same.

20 9. The method of receiving one of two signals occupying a common portion of two overlapping frequency bands, the stronger signal being frequency modulated, which comprises receiving said signals together, modifying the combined signals by increasing the ratio of the stronger signal to the other signal, feeding back a portion of the modified signals at their basic frequency, and reacting the fed-back portion with the signals prior to modification so that at the point of feed back, the basic frequencies of the portion of the signals fed back and of the received signals are the same.
